BAR STOOL OR THE LIKE

Cecilio I. Lazo De La Vega, P.O. Box 554,
Valdosta, Ga. 31601

Filed Sept. 7, 1972, Ser. No. 287,035

Term of patent 14 years

Int. Cl. D6—01

U.S. Cl. D6—32

FIG. 1 is a front elevational view of the first embodiment of a curved seat and back rest of a bar stool showing my new design;

FIG. 2 is a side elevational view thereof, partly broken away for clarity;

FIG. 3 is a rear elevational view thereof;

FIG. 4 is a top plan view of the seat and back rest taken along line 4—4 of FIG. 1;

FIG. 5 is a front elevational view of the second embodiment of a bar stool showing my new design;

FIG. 6 is a side elevational view thereof;

FIG. 7 is a rear elevational view thereof; and

FIG. 8 is a top plan view of the seat and back rest taken along line 8—8 of FIG. 5.

I claim:

The ornamental design for a bar stool or the like, substantially as shown and described.
